UNITED STATES PATENT OFFICE

ALFRED GEORGE BEECH OWEN, OF SUTTON-COLDFIELD, AND ROBERT WILFORD DOWNS,
OF RUSHALL, WALSALL, ENGLAND

VEHICLE WHEEL

Application filed September 23, 1931, Serial No. 564,646, and in Great Britain May 10, 1930.

This invention relates to the type of vehicle wheel in which the securing nuts are enclosed in a relatively deep and substantially cylindrical casing, the outer end of the casing having usually been closed by a cap which must, of course, be detachable in order to provide access to the securing nuts. In the case of wire wheels the casing has usually formed the outer hub or shell to which the spokes are attached, whereas in the case of sheet metal wheels the casing has been attached to the outer surface of the nave of the wheel. It has heretofore been usual to cut out the outer end of the casing except for a narrow inwardly extending flange or gallery, and in some cases this flange has been utilized for the engagement therewith of spring clips carried by the cap. In other cases spring clips have been mounted inside the casing, and have been adapted to engage with an inwardly extending flange of the cap.

The cap, which has been formed of light sheet metal, has been heretofore provided with a peripheral flange to rest on the outer end of the casing as well as with the above mentioned inward flange to enter the said end, necessitating the formation of the cap by spinning instead of simply by pressing. For the above reasons the cap has been comparatively expensive to manufacture, and, owing to the double thickness of metal where the peripheral flange is placed, a crevice exists into which penetrates acid during the plating process which results in corrosion.

According to the main feature of the present invention, the casing is permanently bridged over at its outer end with a wall which is rigid therewith but has relatively large holes through the end in positions over the nuts to afford access thereto. The end closure is preferably pressed in one piece with the side wall of the shell.

Owing to the fact that the nuts are situated somewhat close to the wall of the casing the holes in the end conveniently have their centres somewhat inwards of the axes of the nuts, and they are relatively large so that a person's fingers can be easily inserted for removing the nuts or putting them in place. To facilitate this the holes may be widened

somewhat at those parts which lie near to the peripheral wall of the casing. Each hole may, if desired, suffice for two or more nuts.

The leaving of the end intact with the casing gives it considerably increased strength, so that, if desired, a lighter gauge metal may be used; but, in the case of a wire wheel, it may be found expedient to provide an interior metal band through which the inner ends of the outer set of spokes are passed, such band being a good fit within the casing and being preferably tacked thereto by spot welding. The band may, however, be unattached to the casing as the spokes will draw it securely against the inner wall thereof, to facilitate which, the band may be split if necessary. The provision of the band renders it a simple matter to form the countersinks for the holes, as this can be done before the band is put in place.

The metal of the end of the casing at the middle thereof is utilized as a medium for securing the cap in place, and the latter may be formed as a simple pressing which, when secured in place, is pulled up against the end wall of the casing. A very simple and inexpensive form of pressing is all that is required because there is no inward or peripheral flange needed, a central securing means being sufficient to keep the cap properly in place. As there is no spinning operation required, the cap may be made of steel instead of brass as has heretofore usually been necessary.

The securing means for the cap may consist of a central set screw, the head of which may lie within a recess pressed in the centre of the cap while the shank passes through a hole therein and screws into the centre of the outer wall of the casing or a fitting secured thereto. When it is required to remove the wheel the screw can be readily removed, such as by the use of a coin fitted into a milled slot in a manner well-known. The screw may, however, be rigidly secured to the cap in which case the cap turns with the screw. A headed pin with a spring gripping device at its inner end for engagement with the hole in the centre of the end wall of the casing

may be utilized, or any other type of spring fastening as will be readily understood.

The cap may be pressed to any desired shape adapted to fit up against the outer surface of the end wall of the casing; but it should preferably terminate at its periphery in an edge which is presented to the said end wall so that it obtains a good consistent hold thereon the whole way round. The edge may be beaded, if desired, for additional strength. Owing to the fact that there is a considerable amount of spring between the middle of the cap and the centre of the end wall, the securing screw has no tendency to come undone.

In any case the inner end of the casing may be closed by a separate disc of metal welded at its periphery to the inner edge of the peripheral wall of the casing and having the bolt holes formed through it. In the case of a wire wheel the said disc may be flared back and the inner edge of the casing similarly flared to receive it, the two being welded together at their edges, the spokes passing through both in a well known manner. In the case of a sheet metal wheel, the disc may be of thicker gauge and be inserted into the inner end of the casing and welded therein leaving a square corner. In what is known as a brake-drum type of wire wheel the casing may be welded, riveted or otherwise secured at its inner edge to the brake drum or brake drum cover.

Two convenient practical applications of the invention are described with reference to the drawings herewith of which:—

Figure 1 is a transverse section through a wheel hub shell constructed according to this invention; but showing the fixed hub and securing nuts in elevation.

Figure 2 is a front elevation of the hub shell shown in Figure 1 with the cap secured in place.

Figure 3 is a view corresponding to Figure 2 but with the cap removed; and

Figure 4 is a fragmentary sectional view to an enlarged scale to illustrate the means for securing the cap.

Referring first to Figures 1 to 4, A is the main portion of the hub shell comprising a peripheral wall *a* and a fore end *b* constituting a bridge. The rear end of the shell is constituted by a disc D through which are formed the holes through which the securing bolts *j* pass when the shell is in place over the fixed hub B. The disc D is flanged forwardly and then rearwardly at *d* and the inner end of the wall *a* is flared to fit over it forming two thicknesses of metal which may be welded together at their edges. The inner ends of the inner set of spokes *e* pass through these two thicknesses and tend to hold them in proper relationship to each other whereby the welding referred to is not essential.

The wall *a* and fore end *b* are pressed out

from a metal blank and apertures *f* are cut out from the fore end *b* to allow of a brace or other implement being inserted for engagement with the nuts *j*. It will be seen that the apertures are widened out towards the periphery of the shell to allow the fingers to be inserted to remove a nut or start it upon its thread. It will be seen that the portions of metal *f'* left between the apertures afford great strength to the shell and that the central portion *f''*, designated in Figure 3 forms a convenient anchorage for the securing means for the cap G. Any suitable securing means may be provided for the cap but it is found in practice that a set screw *g*, passing through a hole in the cap and screwing into a fitting *h* set in the centre of the portion *f''*, affords the most practical means, as shown in Figure 4. The edge of the cap G may be left plain or be beaded; but such edge should be allowed to come first into engagement with the fore end *b* so that, when the screw is tightened up a springing effect is produced tending to keep the screw from coming undone. The screw is kept in permanent engagement with the cap by the split cotter *g'* see especially Figure 4, and of course, there is sufficient space left between the cap and the said bridge to allow for the springing effect.

As shown in Fig. 1, E is a metal ring placed in the forward corner of the shell, where the outer set of spokes *e* pass through, so as to obtain extra strength at such place. The ring may be welded in place but such is not necessary as the spokes tend to pull the ring into close relationship with the shell. The countersinks for the spoke heads may conveniently be formed in the holes in the ring E before it is put in the shell.

Having fully described our invention what we claim and desire to secure by Letters Patent is:—

1. A detachable wheel hub comprising a casing adapted to be secured to a fixed hub having a circular series of attaching studs, a ring disc rigidly attached to the inner end of the casing and extending radially inwardly therefrom, having holes therethrough through which said securing studs are adapted to pass, a wall rigid with said casing and bridging across the end thereof over the end of said hub and axially spaced from the outer end thereof, said wall having apertures in axial alignment with said studs, through which apertures a suitable implement can be projected to engage securing nuts on said studs.

2. A detachable wheel hub comprising a casing adapted to be secured to a fixed hub having a circular series of attaching studs, a ring disc rigidly attached to the inner end of the casing and extending radially inwardly therefrom, having holes therethrough through which said securing studs are adapt-

ed to pass, a wall rigid with said casing and bridging across the end thereof and spaced from the outer end of the hub, said wall having apertures in axial alignment with said studs, through which apertures a suitable implement can be projected to engage securing nuts on said studs, and a detachable cap to cover said wall and the apertures therein, and a screw passing through the center of said cap and screwing into the center of said wall.

3. A detachable wheel hub comprising a casing adapted to be secured to a fixed hub having a circular series of attaching studs, a ring disc rigidly attached to the inner end of the casing and extending radially inwardly therefrom, having holes therethrough through which said securing studs are adapted to pass, a wall rigid with said casing and bridging across the end thereof and spaced from the outer end of the hub, said wall having apertures in axial alignment with said studs, through which apertures a suitable implement can be projected to engage securing nuts on said studs, and a detachable resilient metal cap to cover said wall and the apertures therein, and means for detachably securing said cap to the central portion of said wall.

4. A detachable wheel hub, comprising a casing surrounding and adapted to be secured to a fixed hub, said hub having a series of attaching studs, and said studs having securing nuts, the aforesaid casing providing an anchorage at its inner end for the inner set of spokes and an anchorage at its outer end for an outer set of spokes, a ring disc rigidly attached to the inner end of the casing and extending radially inwardly therefrom, having holes therethrough through which said securing studs are adapted to pass, a wall integral with said casing and bridging across the end thereof and spaced from the outer end of the hub, said wall having relatively large apertures in axial alignment with said studs to permit of insertion of a person's fingers for removing or replacing the nuts on the studs, and a cap detachably secured to an intermediate portion of the aforesaid bridging wall to cover up the apertures in said wall.

In witness whereof the said ALFRED GEORGE BEECH OWEN has hereunto signed his name this 27 day of August, 1931.

A. G. B. OWEN.

55 In witness whereof the said ROBERT WILFORD DOWNS has hereunto signed his name this 2nd day of Sept., 1931.

R. W. DOWNS.
